(57) **CLAIM**

The ornamental design for a glass watering device, as shown
and described.

DESCRIPTION

FIG. 1 is a perspective view of the glass watering device
showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a cross-sectional view thereof marked in FIG. 2.
The drawings contain a symbolic break. The portion
between the break lines forms no part of the claimed design.
The long dash-short dash lines illustrate a symbolic break
such that the portion between the long dash-short dash lines
forms no part of the claimed design.
